ATTORNEY'S

UNITED STATES PATENT OFFICE.

JOSEPH J. ENGLERT, OF CHICAGO, ILLINOIS.

TIE DEVICE.

1,367,029.

Specification of Letters Patent.

Patented Feb. 1, 1921.

Application filed July 10, 1918. Serial No. 244,297.

To all whom it may concern:

Be it known that I, JOSEPH J. ENGLERT, a citizen of the United States, residing at Chicago, in the county of Cook and State of Illinois, have invented new and useful Improvements in Tie Devices, of which the following is a specification.

This invention relates to devices employed for securing the contents of paste-board, wooden and other boxes or containers against pilfering, and its object is to provide a very simple, cheap and easily applied device of this kind.

With the object stated in view, the invention consists in a novel combination and arrangement of parts to be hereinafter described and claimed, and in order that the same may be better understood, reference is had to the accompanying drawing forming a part of this specification.

In the drawing,

Figure 1 is an elevation of one of the tie devices;

Fig. 2 is a perspective view showing the position of the tie devices as applied to the container, and before being tightened up;

Fig. 3 is a plan view showing the method of tightening up the tie devices, and

Fig. 4 is a perspective view showing another application of the invention.

Referring specifically to the drawings, 5 denotes a paste-board, wooden or other shipping container to which the invention is applied. In order to protect the contents of the container against pilfering, there is provided a tie device in the form of two endless loops 6 of wire or other cheap material having sufficient flexibility to stand twisting. The ends of the wire are joined 40 by twisting the same together as shown at 7; or they may be fastened together in any other suitable manner immaterial to the present invention. These wire loops will be made in various sizes to fit around containers of different sizes, and for greater convenience in applying the same they will also be shaped to conform to the shape of the containers. The drawing shows a rectangular container, and hence the loop is given 45 a corresponding shape. It will be noted that three sides of the loop fit the sides of the container snugly, and the fourth side

of the loop is bowed outward from the corresponding side of the container as shown at 8. The loop is manufactured in this 55 shape, and hence when it is applied to the container, the portion 8 forms a slack in the loop. Ordinarily, two tie wires are employed, they being placed around the container at right angles to each other, with 60 the slack portions 8 intersecting as shown in Fig. 2. A twisting tool is now applied at the intersection of the parts 8 and the two wires lengths are twisted together as shown at 9 in Fig. 3 to take up the slack, which 65 leaves the two loops drawn tightly around the container. Any suitable tool can be used for making the twist 9. After being tightened up as described, the loops cannot be slipped off the container, nor can they be 70 removed without breaking the same, so that the contents of the container are now safe from being pilfered.

The tie device can be made, properly shaped and dimensioned, by automatic machinery, and it can therefore be cheaply produced. A shaped tie device is also easier to apply than one which must first be bent into shape to fit the container, and which cannot, without considerable difficulty, be 75 drawn tight around the container. The present device, as hereinbefore described is produced in proper shape to tightly fit the containers except for the portions 8 which are twisted together to take up the slack 80 85 after the two loops are in place on the container.

Fig. 4 shows a tie device consisting of three loops, two of which extend around the container crosswise as shown at 10, and the 90 third one lengthwise as shown at 11.

I claim:

A tie device comprising a pair of separate flexible members, each of which is pre-shaped to produce a portion tightly fitting 95 the part to which the device is to be applied and another portion which is bowed outwardly from said part, said bowed portions intersecting, and being twisted together at their intersection to tightly fit the parts 100 from which they previously bowed outwardly.

In testimony whereof I affix my signature.
JOSEPH J. ENGLERT.
